CLAIM

I claim the ornamental design for a tub spout, as shown and described.

DESCRIPTION

FIG. 1 is a front, top, right side perspective view of a tub spout showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, bottom, left side perspective view thereof. Broken lines of the disclosure represent portions of the tub spout that form no part of the claimed design.

1 Claim, 5 Drawing Sheets(56)
